TURBINE CONTROL APPARATUS

John R. Hagemann, Wauwatosa, Wis., assignor
to Allis-Chalmers Manufacturing Company,
Milwaukee, Wis., a corporation of Delaware

Application January 22, 1942, Serial No. 427,698

9 Claims. (Cl. 137—158)

This invention relates generally to control mechanism for prime movers and more particularly to an acceleration responsive control therefor.

The invention is particularly applicable to large capacity prime movers driving loads which are subject to sudden removal, such for example, as large elastic fluid turbine driven electric generator units, since after a sudden loss of load, a short but appreciable period of time is required for the speed of the turbine to accelerate sufficiently to render a conventional speed responsive governor operative to close the turbine admission valve. The continued admission of the steam or other working fluid during said period of time produces a degree of overspeed which is usually sufficient to effect an operation of the overspeed trip mechanism to stop the turbine. Operation of the overspeed trip mechanism is objectionable in such instances as it necessitates a manual operation of the massive throttle valve and a resetting of the overspeed trip mechanism which causes considerable delay before the turbine can be again rendered operative to carry load.

Attempts have been made to prevent an immediate operation of the overspeed trip mechanism in response to a sudden loss of load by the inclusion of a solenoid controlled pilot valve which is operatively associated with a fluid pressure relay having a motor operative to open and close the turbine admission valve. Energization of the pilot valve solenoid is controlled by an electromagnetic relay connected in circuit with a current transformer operatively associated with the power leads of the turbine driven generator. Theoretically this type of control should function satisfactorily but in actual tests it has been found entirely too sluggish to accomplish the desired result, probably due to residual magnetism in the armatures of the pilot valve solenoid and the electromagnetic relay.

Attempts have also been made to prevent operation of the overspeed trip mechanism in response to a sudden loss of load by employing a combination inertia and centrifugal governor for actuating the prime mover throttle or admission valve. However, this form of control has also proved impractical to accomplish the desired result since although the modifying action of the inertia element in response to a sudden loss of load does effect a movement of the throttle toward its fully closed position, its action in this respect is necessarily limited. Consequently, the continued admission of the working fluid, even

though at an appreciably reduced rate, together with the working fluid in the turbine when the load is dropped, is usually sufficient to produce a degree of overspeed which is effective to operate the overspeed trip mechanism to stop the turbine.

It is therefore the primary object of this invention to provide an improved control mechanism for prime movers which will sufficiently minimize the increase in speed accompanying a sudden removal or decrease in the load thereof to prevent the operation of the associated overspeed trip mechanism.

In accordance with this invention, the above mentioned results are accomplished by providing in addition to the usual centrifugal governor and the usual overspeed trip device, a mechanism which effects an immediate closing of the prime mover admission valve whenever the speed of the prime mover is accelerated in excess of a predetermined rate. In other words, the controlling factor is the rate at which the speed increases and not the extent of the increase and consequently, the centrifugal governor, the overspeed trip device, and the acceleration responsive mechanism normally operate entirely independent of each other.

The invention accordingly consists of the various details of construction, combinations of elements and arrangements of parts as is more fully set forth in the accompanying claims and in the detailed description, in which:

Fig. 1 schematically illustrates an elastic fluid turbine control system embodying the invention;

Fig. 2 is a partial sectional view taken on line II—II of Fig. 1;

Fig. 3 is a partial side view of the inertia governor showing the dashpot connection; and

Fig. 4 is an enlarged sectional view of the dashpot piston.

Referring to Fig. 1 of the drawing, it is seen that the control system is applied to an elastic fluid turbine 1 and comprises a back pressure regulator or governor 2, a speed governor 3, an inertia governor 4, a means or operator 6 which is operatively connected with a turbine admission valve 7 and which is controllably connected with the back pressure regulator 2, the speed governor 3 and the inertia governor 4, and an overspeed trip device 8 which is operatively connected with a turbine cut-off valve 9 and which is also controllably connected with the operator 6. In an actual installation, the arrangement of the valves 7 and 9 in the motive fluid supply line 10 would probably be the reverse of that herein shown which was selected solely to effect a sim-

plification of actuating lever arrangements. However, insofar as this invention is concerned, any valve arrangement is sufficient which will effect the mode of control hereinafter described.

The back pressure regulator 2 includes a double acting servomotor 11 having a piston 12 and a dashpot 13, a pilot valve structure 14 including a reciprocable valve element 16 controlling the operation of the piston 12, and a pressure responsive device 17 including a flexible bellows 18 having a motion transmitting part 19, a biasing spring 21 having one end seated on the part 19 and having its other end engaging an adjustable seat 22 carried by a rotatable sleeve member 23, and a rod 24 extending loosely through the sleeve member 23 and having one end engaging the part 19 and having its other end operatively connected with one end of a rigid bar 26 which is in effect fulcrumed on the bracket 27 by means of a flat spring member 28. The other end of the bar 26 is operatively connected with the upper end of a rod 29 which extends into the bore 31 in the valve element 16 and engages same to effect movements thereof. The valve element 16, the rod 29 and the bar 26 are maintained in operative engagement by the spring 32 disposed beneath the valve element 16. The valve structure includes a space 33 which is connected with a fluid pump 34 by means of pipes 36, 37 and 38 and the valve element 16 controls the flow of fluid from said space through the conduits 39 and 41. The arrangement is such that when valve element 16 is in the position shown, no fluid flows through the pipes 39 and 41; that when the valve element 16 moves upward from the position shown, fluid under pressure flows through the pipe 41 and the pipe 39 is placed in communication with a drain pipe 42, thereby effecting a downward movement of servomotor piston 12; and that when the valve element is moved downward from the position shown, fluid under pressure flows through pipe 39 and the pipe 41 is placed in communication with a drain pipe 43, thereby effecting an upward movement of the servomotor piston 12. Pipe 43 is in communication with pipe 42 and the latter is connected with a fluid reservoir 44 with which the pump 34 is operatively connected. The piston 12 is provided with an upwardly extending rod portion 46 which is operatively connected with one end of a lever 47 having an intermediate portion fulcrumed on a bracket 48 carried by the valve structure 14. The other end of lever 47 is provided with an apertured spring seat 49 through which the rod 29 extends and a spring 51, which surrounds the rod 29, has one end engaging said seat and has its other end engaging the seat 52 secured to the rod 29. The lever 47 together with its operative connection with the piston rod 46 and the valve rod 29 constitutes a return mechanism for the valve element 16. The bellows 18 of the pressure responsive device 17 is subjected to the exhaust pressure of the turbine 1 by means of a pipe connection 53 and the arrangement is such that in response to a decrease in exhaust pressure, spring 21 effects a downward expansion of bellows 18 and as a result the springs 32 and 51 effect an upward movement of valve element 16, a clockwise movement of bar 26, and a downward movement of rod 24, thereby maintaining said rod in engagement with the part 19. An increase in exhaust pressure effects a contraction of bellows 18 and a corresponding upward movement of part 19 and rod 24; the latter effecting a counterclockwise movement of

bar 26 and a downward movement of rod 29 and valve element 16. Movement of valve element 16 effects the previously described movements of the servomotor piston 12 and a further description of the operation of the back pressure regulator, which is conventional in all material respects, is believed unnecessary for a complete understanding of this invention.

The speed governor 3 includes a conventional flyball mechanism 54 which is operatively mounted on a spur gear shaft 56 for rotation therewith and which is operatively connected with one end of a coaxially slidable rod member 57. Shaft 56 is connected by gearing 55 to a shaft 58 which in turn is geared to the turbine shaft 59, thereby rendering the flyball mechanism 54 responsive to the turbine speed. Rod 57 has its other end operatively connected with one end of a lever 60 having an intermediate portion thereof adjustably fulcrumed at 61 and having its other end held in operative engagement with the upper end portion of a servomotor pilot valve element 62 by means of a spring 65. The servomotor embodies a double acting piston 64 which surrounds the valve element 62 and which includes a fluid pressure space 66 operatively connected with the pump 34 by means of pipes 67, 37 and 38. The servomotor arrangement is such that when the valve element 62 is moved downward from the position shown, fluid under pressure flows into the space 68 and through the port 69 into the space 71 at the top of the piston and the fluid in the space 72 at the bottom of the piston flows through port 73 into space 74 and through port 76 into the drain pipe 77, thereby effecting a downward movement of the piston 64; and that when the valve element 62 is moved upward from the position shown, fluid under pressure flows into the space 74 and through port 73 into the space 72 at the bottom of the piston and the fluid in the space 71 at the top of the piston flows through port 69 into space 68 and through port 78, the space 79 and into the drain pipe 80, thereby effecting an upward movement of the piston 64. Piston 64 has a rod portion 81 which is in the nature of a sleeve and which is operatively connected with one end of a lever 82 having an intermediate portion 83 fulcrumed on a stationary bracket 84. The other end of lever 82 is held in operative engagement with the upper end of a link 86 by means of a spring 85 and a lever 88 which has an intermediate portion fulcrumed on the piston rod 46 of servomotor piston 12 has one end held in operative engagement with the lower end of link 86 by means of a spring 87 and has its other end pivotally connected with an end portion of a link 89. Upward movement of link 89 is limited by an adjustable stop device 91 which carries the bracket 84. The other end of link 89 is operatively connected with a rock shaft 92 which in turn is operatively connected with one end of a link 93 and it should be obvious that the previously described connections render the servomotor pistons 12 and 64 of the back pressure regulator and the speed governor, respectively, jointly and severally operable to effect a rocking movement of the shaft 92 and a corresponding reciprocation of the link 93.

The inertia governor 4 includes a shaft 94 which is also connected to the shaft 58, the gearing 55, a disk member 96 which is secured to the shaft 94 for rotation therewith, a sleeve structure 97 which is rotatably mounted on the shaft 94 and which is connected to the disk member 96 by means of a torsion spring 98 disposed in concent-

tric relation about the shaft 94, and a bearing structure 99 in which the upper end of the shaft 94 is journaled. The upper end portion of the shaft 94 is provided with an axial bore 101 and radially extending bores 102 which place the axial bore 101 in communication with a pipe 103 by means of the annular space 104, bore 106 and annular space 107 provided in the bearing structure 99. Shaft 94 is also provided with another set of radially extending bores 108, which are arranged to place the axial bore 101 in communication with the slots 109 in the sleeve member 97 when the shaft 94 and the sleeve member 97 assume a predetermined angular relation. Slots 109 are provided with drain passages 111 and the arrangement is such that when the turbine is accelerated in excess of a predetermined rate, the shaft 94 is moved relative to the sleeve member 97 a sufficient distance in the direction indicated by the arrow in Fig. 2 to place the bores 108 in communication with the slots 109, thereby placing the annular space 104, which is connected with the pump 34 by means of a pipe 112 containing a suitable constriction 113 and the pipe 38, with the drain passages 111. Disk member 96 is provided with a dashpot mechanism 114 and a diametrically disposed balancing weight 116, but if desired, another dashpot may be employed in place of the weight 116. The dashpot mechanism includes a piston 117 (see Fig. 4) which is provided with a plurality of openings 118, an annular valve member 119 arranged to close said openings, a weak spring 121 acting to maintain the valve member in a position closing said openings, and one or more slots 122 in the periphery of the piston 117. Piston 117 is provided with a stem 123 which is operatively connected with a slot 124 provided in the adjacent depending portion of the sleeve member 97 (see Fig. 3) by means of a bell crank lever 126 journaled on a bracket 127 carried by the disk member 96. The arrangement is such that when the acceleration of the turbine is sufficiently rapid to effect an angular movement of the shaft 94 and the disk member 96 secured thereto relative to the sleeve member 97 (note the arrow shown in Fig. 2), piston 117 is moved upward and affords but little resistance to such movement since the resulting pressure and suction acting on the top and bottom surfaces of the valve 119 respectively causes the valve to immediately uncover the openings 118; and that when the acceleration decreases below said predetermined rate, the spring 121 causes the valve 119 to again cover the openings 118, thereby rendering the spring 98 ineffective to rapidly return the piston 117 to the position shown. The rapidity with which the piston is returned to said position is obviously determined by the number and the size of the peripheral slots 122.

The fluid operator 6 includes a double acting power piston 128, a hollow valve 129 controlling operation of piston 128, a hollow double acting piston 131 which has its bottom wall bolted to the spider 130 provided on the valve 129, and a pilot valve 132 extending coaxially within the piston 131 for controlling same. Valve 129, which is disposed within a stationary sleeve member 133 and forms therewith an annular space 134 communicating with the fluid supply pipe 38 by means of a bore 136, an annular space 137 and the bores 138, controls a plurality of upper and lower ports 139 and 141, respectively, which communicate with the annular spaces 142 and 143 and the passages 144 and 146 respectively. The space 147 within and beneath the valve 129 com-

municates with a drain pipe 148 which in turn communicates with the reservoir 44. The arrangement is such that when the valve 129 is moved upward from the position shown, fluid under pressure flows from the annular space 134 through the ports 139 into the space 142 and through the passage 144 to the space 149 at the top side of the piston 128 and the fluid in the space 151 beneath the piston 128 flows through passage 146, annular space 143, ports 141, and space 147 into the drain pipe 148, thereby effecting a downward movement of the piston 128; and that when the valve 129 is moved downward from the position shown, fluid under pressure flows from the annular space 134 through ports 141 into the space 143 and through the passage 146 into the space 151 at the bottom of the piston 128 and the fluid in the space 149 at the top of the piston 128 and the fluid in the space 149 at the top of the piston 128 flows through the passage 144, annular space 142, ports 139, the interior of valve 129, and space 147 into the drain pipe 148, thereby effecting an upward movement of the piston 128. Piston 128 is provided with a rod portion 152 which has an intermediate part operatively connected with the turbine admission valve 7 by means of a bell crank lever 153 fulcrumed on a bracket 154, link 156, and a lever 157 having an intermediate portion fulcrumed at 158. The lower interior portion of piston 131 is counter bored and closed by a cap member 159 to provide an enlarged circular space 161 in which is slidably disposed a hollow piston 162. Upward movement of piston 162 is limited by an annular shoulder 163 and the piston 162, which has a lower portion of reduced diameter, is normally held against said shoulder by fluid under pressure which is admitted to the space beneath the piston by means of a passage 164 terminating at its upper end in an annular groove 166, an annular groove 167 in piston 131 which is always in communication with the groove 166, and a passage 168 which places the groove 167 in communication with a branch pipe 169 which is connected with the fluid supply pipe 103. The interior of piston 162 is provided with an annular flange 171 on which is disposed a spring 172 having its upper end abutting an annular shoulder 173 provided by the counter-boring of the interior of the power piston 131. Spring 172 acts to urge piston 162 downward from the position shown. Pilot valve 132 has a stem portion 174 which extends into the piston 162 and beyond the annular flange 171 provided therein and which is provided with at its lower end a laterally projecting annular part 176 disposed approximately half-way between the bottom surface of the flange 171 and the inner surface of the piston head. The arrangement is such that when the space 60 beneath the piston 162 is connected to a drain pipe or the like, the resulting reduction in fluid pressure permits spring 172 to move the piston 162 downward a sufficient distance to engage the bottom surface of the annular flange 171 with the projection 176 on the pilot valve 132 and thereby effect a downward movement of said valve. A passage 177 places the space 161 in continuous communication with the space 175 immediately beneath the cap member 159 of piston 131, the space 147 and the drain pipe 148. The pilot valve 132 is also provided with axially spaced enlarged portions 178 and 179; the former controlling the flow of fluid from the annular space 181 beneath the piston 131 through the passage 182, the space 183 surrounding an

intermediate stem portion of valve 132, and the port 184 into the annular space 186 at the top of the piston 131 and the latter controlling the flow of fluid from the space 183 through the port 187 into the annular space 188 and through the passage 189 to the space 175, thereby placing the space 186 in communication with the drain pipe 148.

The space 181 is in continuous communication with the source of fluid under pressure, the pump 34, by means of a passage 191 which is in communication with the passage 136 and thereby pipe 38. The motion producing portion of the piston surface which is acted upon by the fluid in the space 181 is materially less than that acted upon by the fluid in the space 186 and, as a result, the arrangement is such that when the pilot valve 132 is moved downward from the position shown, fluid under pressure flows from the space 181 through the passage 182, space 183, port 184 and into space 186, thereby effecting a downward movement of the piston 131 which is sufficient to bring the passage 182 in closing relation with the enlarged portion 178 of the pilot valve and that when the pilot valve 132 is moved upward from the position shown, fluid in the space 186 flows through port 184, space 183, port 187, space 188, passage 189, spaces 175 and 147, and into the drain pipe 148, thereby effecting an upward movement of the piston 131 which is sufficient to bring the port 187 in closing relation with the enlarged portion 179 of the pilot valve.

As previously pointed out, a movement of valve 129, which is secured to the cap portion 159 of piston 131, produces an opposite movement of piston 128 and it should therefore be obvious that whenever the pilot valve 132 moves downward, the piston 131 and valve 129 also move downward and the piston 128 moves upward and that whenever the pilot valve 132 moves upward, the piston 131 and valve 129 also move upward and the piston 128 moves downward. The upper end of piston rod 152 is operatively connected with one end of a lever 192 which has an intermediate portion held in operative engagement with the upper end portion of the stem of pilot valve 132 by means of a spring 190 and which has its other end held in operative engagement with the end of link 93 by means of a spring 95. An upward movement of piston 128, which is effected by a downward movement of pilot valve 132, piston 131 and valve 129, produces a clockwise movement of lever 192 about its point of connection with link 93 which in turn effects an upward movement of pilot valve 132 and the return of pilot valve 132, piston 131 and valve 129 to the positions shown. Obviously, a downward movement of piston 128 will also effect a return of the pilot valve 132, the piston 131 and the valve 129 to the positions shown. Bell crank lever 153, link 156 and lever 157 render upward and downward movements of piston 128 operable to effect closing and opening movements of the turbine admission valve 7, respectively.

The overspeed trip mechanism 8 includes a conventional flyball mechanism 193 which is operatively connected with the turbine shaft 59 and with an axially movable rod 194. The arrangement is such that when the turbine speed exceeds a predetermined maximum, the flyball mechanism 193 moves the rod 194 axially toward the left as viewed in Fig. 1 and against the pivoted latch member 196 with sufficient force to disengage same from the reciprocable locking bar 197. Bar 197 is operatively connected with the turbine

cut-off valve 9 by means of a rock shaft 198, a link 199 on which is mounted a suitable weight 201, a bell crank lever 202, link 203, and a pivoted latch member 204 which is arranged to engage and hold the axially movable member 206 of valve 9 in the position shown. Member 206 which is provided with a radially projecting and axially extending rotation preventing rib or key 207, is slidably mounted in the valve casing 9 and upward movement thereof is limited by an annular bottom flange 208. The valve 9 also includes a plug portion 209 and a stem portion 211 which extend through and threadably engage an internally threaded bore 212 which extends axially through the member 206. A spring 213 urges the valve toward its fully closed position and the arrangement is such that with the parts in the position shown, disengagement of the latch member 196 results in the weight 201 effecting a downward movement of the link 199 which in turn effects (1) a counterclockwise movement of rock shaft 198 and a downward movement of the locking bar 197 and (2) a clockwise movement of bell crank 202 and the disengagement of the latch member 204 from the member 206 whereupon the spring 213 effects a closure of the valve 9; the member 206 moving downward with the valve stem 211. The valve 9 remains closed and the flow of motive fluid terminates, irrespective of the position of the admission valve 7, until the overspeed trip mechanism is again reset to hold the valve 9 open. Resetting of the overspeed trip mechanism 8 is preferably accomplished by first turning the valve stem 211, which effects an upward axial movement of member 206, until the flange 208 thereon engages the inner surface of the valve casing as shown; then raising the weight 201 and link 199 until the locking bar 197 is in a position to be engaged by the latch member 196 (this movement of link 199 also engages the latch member 204 with the valve member 206), then moving the latch member 196 into locking engagement with the bar 197 which retains the parts, with the exception of the plug member 209 which is still in closed position, in the relative positions shown, and then continuing to turn the valve stem 211 until the plug member is moved upward sufficiently to effect the desired degree of valve opening. Rock shaft 198 is also operatively connected with a balanced valve structure 214 which together with a pipe 216 provides a connection between the fluid supply pipe 112 and the drain pipe 148. Valve 214 includes spaced piston portions 217 and 218 defining therebetween a space 219 which is in continuous communication with the pipe 112. The lower interior portion of the valve casing is enlarged at 221 and a downward movement of the piston portions 217 and 218, which is effected by a release of the overspeed trip mechanism as previously described, places the space 219 and thereby the pipe 112 in communication with the enlarged portion 221 and thereby the drain pipe 148.

Under normal conditions, the speed governor 3, which is operatively connected with pilot valve 132 of the operator 6 by means of lever 82, link 86, lever 88, link 89, rock shaft 92, link 93 and lever 192, operates in response to a decrease in turbine speed and effects an upward movement of pilot valve 132 and thereby a downward movement of piston 128 and an opening movement of the admission valve 7. Obviously an increase in turbine speed effects a downward movement of pilot valve 132 and thereby an upward move-

ment of piston 128 and a closing movement of the admission valve 1. Normally, the back pressure regulator 2, which is operatively connected with the pilot valve 132 by means of lever 88, link 89, rock shaft 92, link 93 and lever 192, operates in response to a decrease in turbine exhaust pressure and effects an upward movement of pilot valve 132 and thereby a downward movement of piston 128 and an opening movement of admission valve 1. Obviously, an increase in turbine exhaust pressure effects a downward movement of pilot valve 132 and thereby an upward movement of piston 128 and a closing movement of admission valve 1. As previously described, the interconnection between levers 82 and 88 renders the speed governor 3 and back pressure regulator 2 jointly and severally operative to vary the position of the turbine admission valve 1.

In the event the speed of the turbine is accelerated in excess of a predetermined rate, the inertia governor 4 immediately operates as previously described and places the ports 108 in communication with the slots 109, thereby connecting the fluid supply line 103 and the branch pipe 169 with the drain passage 111. Pipe 103 receives fluid under pressure through pipe 112 which contains the constriction 113 and because of said constriction, the connection of the pipe 103 to drain passage 111 effects an immediate reduction in the pressure of the fluid in the space beneath the piston 162 and as a result, the spring 172 immediately moves the piston 162 and thereby the pilot valve 132 downward which in turn effects an upward movement of piston 128 and the closure of the turbine admission valve 1. Spring 172 is materially stronger than spring 95 and as a result the above described downward movement of pilot valve 132 is accompanied by a pivotal movement of lever 192 about its point of connection with piston rod 152 and a corresponding compression of the spring 95. Consequently, the upward movement of piston 128 effects, instead of the usual movement of lever 192, i. e., a pivotal movement of the lever 192 about its point of connection with link 93 and a return movement of the pilot valve 132 to the position shown, a pivotal movement of lever 192 about its point of connection with the stem of pilot valve 132 and a further compression of the spring 95. Consequently, the piston 128 now operates to completely close the admission valve 1 rather than to merely move said valve toward its closed position. Therefore, it should now be obvious (1) that the pilot valve 132 remains in the position to which it is moved by the spring 172 until the connection between the pipe 103 and the drain passage 111 is terminated or if in the meantime the overspeed trip mechanism should operate, until the overspeed trip mechanism is again reset which repositions the valve 214 to terminate communication between the pipe 112 and the drain pipe 148; (2) that the dashpot mechanism 114 is operatively associated with the inertia governor to interpose a predetermined time delay between a reduction in the acceleration below said predetermined maximum and the termination of the connection between the pipe 103 and the drain passage 111; (3) that during the time interval the pipe 103 is connected with either the drain passages 111 or the drain pipe 148, the springs 85 and 87, which hold the ends of the levers 82 and 88 in operative engagement with the ends of link 86, render the speed governor 3 and the back pressure regulator 2 inoperative to effect an upward movement of the link 93, i. e., a

movement of the link 93 in a direction tending to effect an opening movement of the turbine admission valve 1; (4) that unless the overspeed trip has operated, the termination of the connection between the pipe 103 and the drain passages 111 immediately restores the system to normal operating conditions, i. e., the admission valve 1 is placed under the control of the speed governor 3 and back pressure regulator 2 which are jointly and severally operative to effect regulating movements thereof; and (5) that the operation of the overspeed trip mechanism effects an immediate closure of the turbine cut-off valve 9 and a substantially simultaneous closing of the turbine admission valve 1, closure of the latter being effected by actuating the valve 214 to place the pipe 112 and thereby the pipe 103 in communication with the drain pipe 148 which, as previously described, renders the spring actuated piston 162 operative to close the admission valve 1 and the speed governor 3 and the back pressure regulator 2 inoperative to effect an upward movement of the link 93.

It should also be obvious that the inertia governor 4 and the overspeed trip mechanism 8 are responsive to entirely different conditions of speed; the former being responsive to the rate of speed increase and the latter being responsive to the extent of speed increase irrespective of the rate of increase. Consequently, if the rate of speed increase is sufficiently rapid, the inertia governor 4 effects an immediate closure of the admission valve 1, which in most instances prevents an insufficient increase in speed for the operation of the overspeed trip mechanism, and after a relatively short time interval again places the admission valve 1 under the control of the speed governor 3 and/or the back pressure regulator 2 without an interruption of power development. However, if the speed gradually increases to an excessive degree, the inertia governor remains inoperative, and the overspeed trip mechanism operates to effect a complete shut-down as previously described.

The invention is applicable to prime movers generally and although it has been illustrated and described in connection with the control of an elastic fluid turbine, it should be understood that it is not desired to limit the invention to either the exact mode of operation or the exact details of construction herein shown and described as various modifications within the scope of the appended claims may occur to persons skilled in the art.

It is claimed and desired to secure by Letters Patent:

1. In combination in a prime mover embodying means for conducting motive fluid to the prime mover and control means including a governing device for automatically regulating the flow of motive fluid to said prime mover in accordance with variations in an operating condition thereof, an inertia device movable independently of said governing device in response to the rate of change of prime mover speed, said control means including at least one part which is moved to a position for effecting a termination of said flow in response to a speed-increasing produced movement of said inertia device, and additional means operative to retain said part in said position for a time interval sufficient to terminate said flow each time said part is so positioned by a speed-increasing produced movement of said inertia device.

2. In combination, a prime mover, means for conducting motive fluid to said prime mover, a first means operative to vary and to terminate the flow of motive fluid to said prime mover, a governing device movable in response to changes in an operating condition of said prime mover, an acceleration device movable independently of said governing device in response to the rate of change of prime mover speed, control means responsive to and rendering said movements of the governing device operative to actuate said first means for varying said flow, and additional control means responsive to and rendering a speed-increasing produced movement of said acceleration device operative to initiate and complete a flow terminating actuation of said first means, said additional control means including time delay apparatus operative to retain said first means in its flow terminating position for a predetermined time interval each time a flow terminating actuation of said first means is initiated by a speed-increasing produced movement of the acceleration device.

3. In combination, a prime mover, means for conducting motive fluid to said prime mover, a first means operative to vary and to terminate the flow of motive fluid to said prime mover, a governing device movable in response to changes in an operating condition of said prime mover, control means including an element responsive to and rendering the movements of said governing device operative to actuate said first means for varying said flow, an acceleration device movable independently of said governing device in response to the rate of change of prime mover speed, and additional control means responsive to said acceleration device and including a movable member controllably associated with said element, said additional means being operative in response to a speed-increasing produced movement of said acceleration device to place said element in a position effective to initiate a flow terminating actuation of said first means and to retain said element in said position for a time interval sufficient for said first means to terminate said flow.

4. In combination, a prime mover, means for conducting motive fluid to said prime mover, a first means operative to vary and to terminate the flow of motive fluid to said prime mover, a governing device movable in response to changes in an operating condition of said prime mover, control means including an element responsive to and rendering the movements of said governing device operative to actuate said first means for varying said flow, a movable member controllably associated with said element and operable, when moved a predetermined distance from one position thereof, to position said element for immediately effecting a flow terminating actuation of said first means, an acceleration device responsive to the rate of change of prime mover speed, and a second means controlled by said acceleration device for effecting said movement of the member and for positioning and retaining same in its said one position, said second means being operative to move said member said predetermined distance from said one position thereof in response to the speed of the prime mover increasing in excess of a predetermined rate.

5. In combination, a prime mover, means for conducting motive fluid to said prime mover, a first means operative to vary and to terminate the flow of motive fluid to said prime mover, a

governing device responsive to changes in an operating condition of said prime mover, control means including an element responsive to and rendering the movements of said governing device operative to actuate said first means for varying said flow, a movable member controllably associated with said element and operable, when moved a predetermined distance from one position thereof, to position said element so that said first means is actuated to quickly terminate said flow, a second means acting to move said member said predetermined distance, an acceleration device responsive to the rate of change of prime mover speed, and additional control means responsive to said acceleration device for positioning and controllably retaining said member in its said one position, said additional means being operative in response to a speed-increasing produced movement of the acceleration device to release said member for a time interval sufficient for said second means to move said member said predetermined distance.

6. In combination, a prime mover, means for conducting motive fluid to said prime mover, a first means operative to vary and to terminate the flow of motive fluid to said prime mover, a governing device responsive to changes in an operating condition of said prime mover, control means including an element responsive to and rendering the movements of said governing device operative to actuate said first means for varying said flow, a movable member controllably associated with said element and operable, when moved a predetermined distance from one position thereof, to position said element so that said first means is actuated to quickly terminate said flow, a second means continuously acting to move said member said predetermined distance, a source of fluid under pressure connected with and operable to position and retain said member in its said one position, an acceleration device responsive to the rate of change of prime mover speed, and additional control means responsive to said acceleration device for quickly reducing the pressure of the fluid acting on said member sufficiently to render said second means effective to move said member said predetermined distance.

7. In combination, a prime mover, means for conducting motive fluid to said prime mover, a first means operative to vary and to terminate the flow of motive fluid to said prime mover, a governing device responsive to changes in an operating condition of said prime mover, control means including an element responsive to and rendering the movements of said governing device operative to actuate said first means for varying said flow, a movable member controllably associated with said element and operable, when moved a predetermined distance from one position thereof, to position said element so that said first means is actuated to quickly terminate said flow, a second means operative to move said member said predetermined distance, an acceleration device movable in response to the speed of the prime mover increasing in excess of a predetermined rate, an overspeed device movable in response to the prime mover attaining a predetermined high speed, a third means operative to position and retain said member in its said one position, and additional control means responsive to and rendering said movements of the acceleration and overspeed devices severally operative to render said third means inoperative for a time interval sufficient for said sec-

ond means to move said member said predetermined distance.

8. In combination, a prime mover, means for conducting motive fluid to said prime mover, a first means operative to vary and to terminate the flow of motive fluid to said prime mover, a governing device responsive to changes in an operating condition of said prime mover, control means including an element responsive to and rendering the movements of said governing device operative to actuate said first means for varying said flow, a movable member controllably associated with said element and operable, when moved a predetermined distance from one position thereof, to position said element so that said first means is actuated to quickly terminate said flow, a second means operative to move said second member said predetermined distance, a third means operative to position and retain said member in its said one position, an acceleration device responsive to the rate of change of prime mover speed, and additional control means responsive to said acceleration device, said additional means being operative in response to a speed-increas-

ing produced movement of the acceleration device to render said third means inoperative for a time interval sufficient for said second means to move said member said predetermined distance.

5 9. In combination, a prime mover, a first means operative to vary and to terminate the flow of motive fluid to said prime mover, a governing device movable in response to changes in an operating condition of said prime mover, an acceleration device movable independently of said governing device in response to the rate of change of prime mover speed, and control means including a part responsive to and rendering movements of said governing device operative to actuate said first means for varying said flow, said control means including at least one additional part responsive to and rendering a speed-increasing produced movement of said acceleration device operative, independently of said governing device, to initiate and continue a flow-terminating actuation of said first means until said flow is terminated.

JOHN R. HAGEMANN.
